(57) **CLAIM**

The ornamental design for the amphibious sport aircraft cockpit and instrument cluster, as shown and described.

DESCRIPTION

The present application relates to commonly assigned U.S. patent application Ser. No. 29/460,782 filed Jul. 15, 2013, entitled Amphibious Sport Aircraft, and U.S. patent application Ser. No. 29/460,776 Jul. 15, 2013, entitled Amphibious Aircraft Hull.

FIG. 1 is a partial left rear perspective view of the amphibious sport aircraft cockpit and instrument cluster showing our new design;

FIG. 2 is a partial right front perspective view thereof;

FIG. 3 is a partial left front perspective view thereof;

FIG. 4 is a partial rear elevational view thereof;

FIG. 5 is a partial right rear perspective view thereof; and,

FIG. 6 is a top overhead view thereof.

The broken lines in the figures represent boundaries that form no part of the claimed design.
